US00D925912S

(12) **United States Design Patent** (10) **Patent No.:** **US D925,912 S**
(45) **Date of Patent:** **** Jul. 27, 2021**

(54) **STORAGE BOX**

(71) Applicant: **Zhejiang Yimei Technology Co., Ltd.**,
Taizhou (CN)

(72) Inventor: **Cai-Fen Lu**, Taizhou (CN)

(73) Assignee: **Zhejiang Yimei Technology Co., Ltd.**,
Taizhou (CN)

(**) Term: **15 Years**

(21) Appl. No.: **29/729,515**

(22) Filed: **Mar. 27, 2020**

(51) LOC (13) Cl. **09-04**

(52) U.S. Cl.

USPC **D3/307**
